PAINT BRUSH

Israel Kantor, Bronx, N. Y.

Application December 13, 1943, Serial No. 514,015

12 Claims. (Cl. 15—248)

1

This invention relates to paint brushes.

It is the main object of the invention to provide a paint brush having improved means for catching and trapping paint or the like coating liquids which would otherwise run down over the handle when the brush is held in certain positions.

A further object of the invention is to provide a paint brush having improved paint trapping means which slowly redelivers trapped paint to the bristles when the head of the brush is below the handle.

A further object of the invention is to provide a paint brush having improved paint catching means which prevents paint dripping from the ferrule when the brush is being wielded or moved from a paint can to a surface to be painted.

An additional object of the invention is to provide a paint brush having improved paint catching and trapping means which can be easily and detachably mounted on the brush.

Still another object of the invention is to provide a paint brush having a paint storage reservoir from which paint is slowly delivered to the bristles of the brush when the brush head is below the handle.

Other objects of this invention will in part be obvious and in part hereinafter pointed out.

The invention accordingly consists in the features of construction, combinations of elements, and arrangement of parts which will be exemplified in the constructions hereinafter described, and of which the scope of application will be indicated in the claims.

In the accompanying drawings, in which are shown various possible embodiments of this invention,

Fig. 1 is a fragmentary side elevational view in partial section of a paint brush having attached thereto a paint catching and trapping means embodying the invention;

Figs. 2 and 3 are back and front views respectively thereof;

Figs. 4, 5 and 6 are sectional views therethrough taken substantially along the lines 4—4, 5—5 and 6—6 respectively of Fig. 1;

Fig. 7 is a sectional view taken substantially along the line 7—7 of Fig. 6;

Fig. 8 is an enlarged sectional view taken substantially along the line 8—8 of Fig. 4;

Fig. 9 is a fragmentary sectional view of a valve for draining paint from the paint trapping means, the same being taken substantially along the line 9—9 of Fig. 6;

Fig. 10 is an inside view of the paint catch-

2

ing and trapping means opened and detached from the paint brush; and

Fig. 11 is a fragmentary side elevational view in section of a modified form of the invention.

Referring now to the drawings, 10 denotes a conventional paint brush comprising a handle 12 and an enlarged brush head 14 to which the usual mass of bristles 16 are firmly secured by a metal ferrule 18.

In accordance with the invention, I provide in conjunction with the brush 10 a means for catching and trapping paint which would otherwise run down over the handle 12 when the head 14 is above the same. Said means is in the form 15 of an attachment 20 which is adapted to be removably secured to the paint brush 10 in a simple and easy manner. The attachment essentially includes means, such as a trough, to catch paint as it runs down the bristles 16 towards the ferrule, a storage reservoir, means to slowly conduct the paint caught in the trough to the reservoir, this means being so constructed that when the bristles are lifted above the brush head after a certain amount of paint is trapped 20 in the reservoir, paint will slowly flow back from the reservoir to the bristles at a rate which is proper for painting, means to drain the reservoir or to fill the same if desired, and means to detachably secure the attachment to the handle 25 of a paint brush.

The paint storage reservoir is in two parts 22, 24 each of which includes an inner wall 26 (Fig. 6) of thin form-maintaining material like sheet metal having a configuration slightly larger than 35 and substantially similar to the configuration of the brush head 14 and ferrule 18. The outer walls 28 of the reservoir are spaced from and parallel to the inner walls 26 whereby to define the two reservoirs which, when the attachment 40 is secured to the paint brush, surround the ferrule. A bottom wall 30 integrally interconnects the side walls 26, 28 of each reservoir. The ends of the reservoir 22 are closed by peaked walls 32 and the end walls of the reservoir 24 45 closed by depressed walls 34 which negatively match the peaked end walls 32 and thus provide a vault joint which securely maintains the two reservoirs in proper relationship when the attachment is on the paint brush.

To facilitate simple detachable attachment of the paint catching and trapping means to the paint brush, the outer walls 28 of the two reservoirs adjacent an end thereof are connected by a long hinge 36. The opposite end of an outer wall of one of the reservoirs has a locking

wire bail 38 pivotally mounted thereon, a vertical reach of said bail being adapted to be sprung over the top of a leaf catch 40 extending from the outer wall 28 of the other reservoir 24.

Attention is called to the fact that both ends of the reservoirs are curved to conform to the configuration of the brush head illustrated, thus improving the esthetic appearance of the attachment and rigidifying the same against collapse. Each of the reservoirs are further reinforced by indentations 42 in the outer walls 28 whose bottoms 44 abut against the inner walls 26 to aid in maintaining the two walls in proper spaced relationship.

The top of each reservoir is closed off by a wall 46 securely fixed to the inner and outer walls 26, 28. At spaced points along this wall through openings 48 are provided from which stub outlets 50 depend. Conduits 52 attached to said outlets serve as the means for slowly conducting paint, caught on the wall 46, to the reservoirs 22, 24.

In accordance with the invention these conduits, which may be made from any form-maintaining material such as rubber, plastic or the like, have a diameter small enough to impede the flow of paint therethrough. The conduits are not small enough to act as capillary tubes and thus prevent the flow of paint, nor are they so large that they allow paint to run rapidly therethrough. I have found that a suitable conduit diameter is in the neighborhood of three-sixteenths of an inch. In order to have the conduits large enough for ready cleaning and yet not let the paint run through the same too quickly, their length may be increased by helically convoluting the same as shown. In this manner the friction head of the conduits, which impedes passage of the paint therethrough, has a large value per unit length measured along the axis of the helix. The convolutions may extend from the top wall 46 to bottom wall 30 and when occupying such a position act as a highly efficient trap which prevents paint from flowing back to the bristles from the reservoir when the handle is higher than the brushhead. To further increase the overall friction head the flow of adjacent conduits may be paired, that is, the convoluted conduits running from adjacent openings 48 may each have one end connected to a stub outlet 50 and the other end to a branch of a Y-fitting 54 to whose trunk there is secured another conduit 56 whose lower free end is disposed near the bottom wall 30. The overall length of these conduits 52, 56 is sufficient to ensure that paint will flow but slowly therethrough. As a matter of fact this length is great enough to prevent the rapid flow therethrough of even thin, relatively watery, coating fluids such as whitewash or shingle paint. Where enamels are to be regularly used the conduits may be made shorter, less convoluted or of a larger diameter.

Paint which accumulates in the reservoir may be drained therefrom by manipulation of a valve 57 (Fig. 9) in each reservoir. Said valves, which are of extremely simple construction, each comprises an orifice 58 in the bottom wall 30 which is normally closed by a tapered valve plug 60 urged against said wall by a spring 62 which is held under compression between the top of the plug and a washer 64 in the reservoir. Said washer lies under a tube 66 which encircles the operating spindle 68 for the valve, the upper end of said tube bearing against packing 70 below

the top wall 46 of the reservoir. The valve spindle passes through said top wall and is bent over to provide a manipulating handle 72 which is received in a notch 74 of a wall 76, shortly to be described. Said notch has a bayonet slot 78 which prevents the handle from being accidentally moved to open the valve.

Both the inner and outer walls 26, 28 of the reservoirs 22, 24 are continued above the top walls 46. The extension of the inner wall 26 is a flange 80 which is inclined towards the bristles 16 and is adapted to have its upper edge firmly engaged against said bristles so that any paint which runs down toward the handle 12 will flow over said flange to the top of the wall 46 where it is caught and will gravitate through the openings 48 and conduits 52, 56 into the reservoirs 22, 24.

To expedite the formation of a tight grip between the flanges 80 and bristle 16 the upper edges of said flanges may be serrated as at 82 (Fig. 1), this construction enabling said edges to better place the bristles under compression and to compensate for any deviations of said edges from rectilinearity.

Flow of paint into the conduits 52 may also be facilitated by providing high spots 84 between the openings 48 and sloping the wall from said high spots to the openings (Fig. 1).

There is a tendency for paint to leak through the junction of the flanges 80 where the end of the reservoir 22, 24 abut. I prevent this by specially constructing the ends of the flanges in the following manner. Each end of the flange 35 associated with one reservoir 22 is provided with an integral inset tongue 86 which is adapted when the attachment 20 is secured to the brush to be captively received in a channel in the matching end of the flange associated with the other reservoir 24. The channel is formed by securing a Z-strip 88 to the inside of the wall 26.

Said inset tongues and Z-strips are continued under the ends of the walls 46, to effect a paint-tight joint of the walls 46 at both ends of the reservoirs.

The extension of the outer wall 28 above the top wall 46 comprises the flange 76 whose outer edge 80 is curled in to permit the paint brush to be substantially tilted, with the head above the handle, without allowing liquid paint accumulated in the trough 92 to run out. Said trough is defined by the wall 46 and the flanges 76, 80. Leakage of paint through the juncture of the flanges 76 is prevented by resilient strips 93.

It will be noted that the inner walls 26 are spaced slightly from the brush end 14 and ferrule 18. However, the attachment 20 must grip the brush firmly at points other than the bristles. For this purpose I provide a plurality of almost vertically disposed, horizontally extending leaf springs 94, 96 on the inner face of the attachment, one edge of said springs being secured to the inner walls 26 and the other edge, when the attachment is closed, frictionally engaging the ferrule 18. The upper spring 94 has its lower edge pressed against said ferrule and the lower spring 96 its upper edge pressed against the ferrule thereby securing a balanced frictional connection between the attachment 26 and paint brush handle on both halves of said attachment.

Additional means may also be provided to aid in preventing shifting of the attachment on the paint brush, said means comprising a clip 98 secured to the bottom wall 30 of each of the reservoirs. Each clip has two inturned fingers 100

which are adapted to flatly press against the bottom of the brush head 14.

It may be mentioned that, although I have shown the two reservoirs as having oppositely facing internally convex shapes, said reservoirs may be joined by eliminating the end walls 32, 34 adjacent the hinge 36 and substituting a flexible connection of leather, rubber or the like between the matching ends of the walls 22, 23 or by interconnecting said reservoirs with a conduit.

To place the attachment on the brush, one reservoir is fitted in proper position on the ferrule and the two halves of the conduit pivoted about the hinge 36 so as to force the two open ends of the reservoirs into contact. The attachment is held in place by locking the bail 38 on the catch 40. For painting, the bristles of the brush are dipped in paint in the customary manner and the brush wielded as usual to paint a surface. Each time the bristles are raised above the handle 12, paint will run down the bristles on to the outer surfaces of the flange 39 and thence on to the top wall 46 where it is caught in the trough 92. From the trough the paint will flow through the conduits 52, 56 into the reservoir. The conduits will pass the paint sufficiently rapidly to prevent any paint from overflowing the lip 90 of the outer flange 76. Once the paint has entered into the reservoirs 22, 24 it is trapped there, since when the bristles of the brush are above the handle 12 paint can only gravitate into the reservoir and when the handle 12 is above the bristles the open ends of the conduits 56 are above the level of the paint in the reservoir.

It may sometimes be desirable to permit the paint which is trapped in the reservoirs to flow slowly back into the bristles when the handle is above the brush head 14. To this end I may modify the foregoing construction in the manner shown in Fig. 11 by providing a set of conduits 52', 56' the free ends 58a of which are relatively close to the top wall 46. With this construction, after a certain amount of paint has accumulated in the reservoirs and the handle 12 is raised above the bristles, paint will flow from the reservoirs back into the bristles. The convoluted conduits will retard the flow of paint to such an extent that the paint will not rush rapidly from the reservoir into the bristles too fast to prevent efficient painting. If desired, the reservoirs may be charged with paint through the valve orifices 58 so as to provide a steady flow of paint to the bristles even though the bristles are never raised above the level of the handle.

I may improve the grip effected between the halves of the attachment 20 and the paint brush by covering the brush head and ferrule with a sheath 102 of a flexible resilient material such as rubber. This sheath will cling to the brush head and ferrule obtaining good frictional contact with said brush head and ferrule on one side and with the springs 94, 96 and fingers 100 on the other side. Said sheath also functions to preserve the ferrule and brush end of the handle by protecting the same from water even when the attachment 20 is removed.

It will thus be seen that there is provided a device which achieves the several objects of this invention and which is well adapted to meet all conditions of practical use.

As various possible embodiments might be made of the above invention, and as various changes might be made in the embodiments above set forth, it is to be understood that all matter herein set forth or shown in the accompanying drawings

is to be interpreted as illustrative and not in a limiting sense.

Having thus described my invention, I claim as new and desire to secure by Letters Patent:

5. A paint brush comprising a trough to catch paint running down from the bristles of the brush when said bristles are above the brush handle, a reservoir and means providing a non-linear passageway of small diameter and long length interconnecting said trough and reservoir which affords a large friction head opposing the flow of paint therethrough whereby paint will slowly flow from said trough to said reservoir.
10. A paint brush comprising bristles, a reservoir and means intermediate said reservoir and said paint brush to permit paint to flow therebetween, said means comprising a non-linear passageway of small diameter affording a large friction head to impede the passage of paint and prevent the same from flowing rapidly from said reservoir to said bristles.
15. For use with a paint brush an attachment comprising a trough to catch paint running down from the bristles of the brush when said bristles are above the brush handle, a reservoir, means including a non-linear passageway of small diameter and relatively long length interconnecting said trough and reservoir which affords a large friction head opposing the flow of paint therethrough whereby paint will slowly flow from said trough to said reservoir, and means to detachably secure said attachment to said paint brush.
20. An attachment as set forth in claim 3 where-35 in the attachment including the trough comprises two parts, a hinge to pivotally connect two matching ends of such parts and a lock to detachably connect the other two matching ends, the pairs of matching ends of the two parts of the trough 30 cooperating to form paint seals.
25. An attachment as set forth in claim 3 comprising two halves, wherein means is provided to pivotally interconnect said halves, wherein the means to secure the attachment to the paint brush includes means to lock the two halves together, and wherein each of the two halves includes one half of the trough, the matching ends of the half of the trough cooperating to form paint seals to connect the two parts of the trough 35 when the two halves are locked together.
30. An attachment as set forth in claim 3 comprising two halves, wherein means is provided to pivotally interconnect said halves, and wherein the means to secure the attachment to the paint brush includes means to lock the two halves together and resilient means to resiliently and frictionally grip the head of the paint brush.
35. An attachment as set forth in claim 3 comprising two halves, wherein means is provided to pivotally interconnect said halves, and wherein the means to secure the attachment to the paint brush includes means to lock the two halves together, a sheath to snugly fit the brush head and cover the same from the bristles to the handle and resilient means to resiliently and frictionally grip said sheath.
40. An attachment as set forth in claim 3 comprising two halves, wherein means is provided to pivotally interconnect said halves, and wherein the means to secure the attachment to the paint brush includes means to lock the two halves together, a rubber sheath to snugly fit the brush head and cover the same from the bristles to the handle and resilient means to frictionally grip said sheath.
45. An attachment as set forth in claim 3 comprising two halves, wherein means is provided to pivotally interconnect said halves, and wherein the means to secure the attachment to the paint brush includes means to lock the two halves together, a sheath to snugly fit the brush head and cover the same from the bristles to the handle and resilient means to resiliently and frictionally grip said sheath.
50. An attachment as set forth in claim 3 comprising two halves, wherein means is provided to pivotally interconnect said halves, and wherein the means to secure the attachment to the paint brush includes means to lock the two halves together, a sheath to snugly fit the brush head and cover the same from the bristles to the handle and resilient means to resiliently and frictionally grip said sheath.
55. An attachment as set forth in claim 3 comprising two halves, wherein means is provided to pivotally interconnect said halves, and wherein the means to secure the attachment to the paint brush includes means to lock the two halves together, a sheath to snugly fit the brush head and cover the same from the bristles to the handle and resilient means to resiliently and frictionally grip said sheath.
60. An attachment as set forth in claim 3 comprising two halves, wherein means is provided to pivotally interconnect said halves, and wherein the means to secure the attachment to the paint brush includes means to lock the two halves together, a sheath to snugly fit the brush head and cover the same from the bristles to the handle and resilient means to resiliently and frictionally grip said sheath.
65. An attachment as set forth in claim 3 comprising two halves, wherein means is provided to pivotally interconnect said halves, and wherein the means to secure the attachment to the paint brush includes means to lock the two halves together, a rubber sheath to snugly fit the brush head and cover the same from the bristles to the handle and resilient means to frictionally grip said sheath.
70. An attachment as set forth in claim 3 comprising two halves, wherein means is provided to pivotally interconnect said halves, and wherein the means to secure the attachment to the paint brush includes means to lock the two halves together, a rubber sheath to snugly fit the brush head and cover the same from the bristles to the handle and resilient means to frictionally grip said sheath.
75. An attachment as set forth in claim 3 comprising two halves, wherein means is provided to pivotally interconnect said halves, and wherein the means to secure the attachment to the paint brush includes means to lock the two halves together, a rubber sheath to snugly fit the brush head and cover the same from the bristles to the handle and resilient means to frictionally grip said sheath.

9. For use with a paint brush an attachment comprising a trough in which paint is caught when the bristles of the brush are lifted above the handle, a reservoir beneath said trough and convoluted conduits of small diameter connecting said trough and reservoir to afford passageways having large friction heads opposing the flow of paint therethrough whereby paint will slowly flow from said trough to said reservoir.

10. For use with a paint brush an attachment comprising a trough in which paint is caught when the bristles of the brush are lifted above the handle, a reservoir beneath said trough, the bottom wall of the trough forming the top wall of the reservoir, and convoluted conduits of small diameter connecting said trough and reservoir to afford passageways having large friction heads opposing the flow of paint therethrough whereby paint will slowly flow from said trough to said reservoir.

11. For use with a paint brush an attachment comprising a trough in which paint is caught when the bristles of the brush are lifted above the handle, a reservoir beneath said trough and convoluted conduits of about three-sixteenths of an inch in diameter connecting said trough and reservoir to afford passageways having large friction heads opposing the flow of paint therethrough

5
15
